Application filed July 3, 1899. Serial No. 722,771. Term of patent 3½ years.

To all whom it may concern:

Be it known that I, WALTER CHARLES MAGEE, a citizen of the United States, residing at New York, in the county of New York and State of New York, have invented and produced a new and original Design to be Worked into or upon Carpeting or Similar Fabrics; and I do hereby declare that the drawing accompanying this specification gives and conveys to any one skilled in the art of carpet-weaving a clear understanding of the same that is sufficient to enable such persons to use my invention.
